METHOD OF AND APPARATUS FOR CLEANING, STERILIZING, AND SMOOTHING BEACHES

Frank B. Hunter, Indianapolis, Ind.

Application October 19, 1931, Serial No. 569,683

13 Claims. (Cl. 4—172)

The present application relates to a method of and means for cleaning, smoothing, and sterilizing bodies of comminuted material, such as sand beaches, and the like. The primary object of the 5 invention is to provide a method of and apparatus for accomplishing these results with respect to the sand beach illustrated and described as an adjunct of the recreation pool disclosed and claimed in my co-pending application, Ser. No. 10 458,133, filed May 31, 1930. Further objects of the invention will appear as the description proceeds.

To the accomplishment of the above and related 15 objects, my invention may be embodied in the form illustrated in the accompanying drawing, attention being called to the fact, however, that the drawing is illustrative only, and that change may be made in the specific construction illustrated and described, or in the specific steps 20 stat-ed, so long as the scope of the appended claims is not violated.

Fig. 1 is a plan view of an installation in accordance with the present invention; and

Fig. 2 is a fragmental section, taken substantially on the line 2—2 of Fig. 1, and on an enlarged scale.

In addition to the difficulties always experienced with sand beaches provided in connection with public swimming pools, and mentioned in my 30 above-identified application, operators of such installations have found that the problems of removing trash, such as waste paper, cigarette, and cigar stubs, bits of food, and the like, from such beaches; smoothing and tamping the beach; and 35 maintaining the beach in a relatively sterile condition are not only difficult of solution, but involve considerable expense if the problems are solved in anything like a satisfactory manner. The installation herein disclosed and claimed 40 solves all of these problems, and does so in a very inexpensive manner.

The recreational installation is indicated generally at 10, and comprises a pool 11 surrounded by a walk 12 which, in turn, is surrounded by the 45 sand beach 13. The beach 13 comprises a basin 14 of concrete or other substantially waterproof material, the basin consisting of a bottom wall 15, an upstanding outer bounding wall 16 and an up-standing inner bounding wall 17. It will be ob- 50 vious that the wall 17, together with the walk 12 and the curb 18 separating the walk from the pool 11 may be considered as a single bounding wall.

The normal water level in the pool is indicated 55 by the reference numeral 31, and it will be seen

that the wall 16 and the wall 17 terminate at levels below such normal water level, the walk 12 sloping slightly, and joining the curb 18 substantially at said level 31. The wall 16 is formed at its outer edge with an upward extension 19 projecting to a level substantially that of the curb 18; and an overflow gutter 20 is formed in the wall 16 immediately adjacent the extension 19. 5

At a plurality of spaced points about the basin 14, there are provided sumps 21 below said basin. 10 A mass of sand, indicated by the reference numeral 22, is filled into the basin 14 to a level 23 materially below the normal water level 31. The bottom wall 15 of the basin 14 is formed with a plurality of apertures 24, each providing communication between the basin and one of the sumps 21. As will be obvious, each of the apertures 24 has a radial length materially less than the length of the corresponding sump 21, and a baffle 25 is provided, depending from the bottom 15 20 15 of the basin and projecting downwardly into the sump 21, but terminating short of the bottom of said sump. As is clearly shown in Fig. 2, the sand mass tends to run in under the baffle 25 and to cover the floor of the sump 21, whereby 25 the sand mass, in cooperation with the bottom 15 of the basin 14 and with the baffle 25, forms a chamber 26, unfilled by the sand.

A conduit 27 communicates at its one end with the body of water in the pool 11, and a valve 28 30 of any desired construction is positioned to control flow of liquid through said conduit. An operating handle 29 is illustrated projecting upwardly through the curb 18, but it will be obvious that any suitable operating means for the valve 35 28 may be provided. In the illustrated embodiment, the conduit 27 communicates with the pool adjacent the periphery of said pool and at a shallow portion thereof, but it will be obvious that the conduit 27 may communicate with the pool 40 at any desired point.

The conduit 27 communicates, as at 30, with the sump 21, thus putting the sump 21, and consequently the basin 14, into communication with the pool 11, such communication being controlled 45 by the valve 28. An outlet conduit 32, to which is preferably connected a suction pump, communicates with the chamber 26 within the sump 21.

After a day's operation of the recreational in- 50 stallation, and after the installation has been closed to the public for the night, the valve 28 may be opened to permit the chlorinated water in the pool 11 to flow to and into the sump 21. The water supply mechanism for the pool is op- 55

erated to maintain the normal water level 31 substantially unchanged, so that the chlorinated water from the pool will permeate the sand mass 22, and a body of chlorinated water will be built 5 up in the basin 14. Flotsam on the surface of the sand mass will, of course, be lifted by the body of water, and the water will flood, at least to some extent, the walk 12, sweeping therefrom bits of undesirable material. The water level is 10 raised sufficiently to permit a surface overflow into the gutter 20, and the level is maintained long enough to permit this overflow to entrain and carry away all bits of flotsam. The gutter 20 may be connected to a sewer, or may be connected 15 to return the overflowing liquid to the water purifying system of the installation.

After the flotsam has been removed, the valve 28 is closed and the suction pump connected to the conduit 32 is put into operation. Because of 20 the specific gravity of the sand particles, the chamber 26 will be substantially free of sand, but will, of course, be filled with water. As the water is removed by the pump from the chamber 26, the water standing in the basin and in the 25 sump is drawn downwardly through the sand mass 22 around the baffle 25 into the chamber 26, and so is withdrawn through the conduit 32. The sand mass will, of course, be somewhat dispersed in the body of liquid within the basin, and as 30 the liquid body is withdrawn, a nice, smooth, compact surface is formed on the sand mass. Particles of material of greater specific gravity than the sand will, in general, be moved downwardly through the mass and away from the surface of 35 the sand.

Because of the fact that chlorinated water from the pool 11 is used for flushing the sand mass, the sand mass is automatically sterilized during the cleaning and smoothing process above described.

40 I claim as my invention:

1. The combination with a sand beach laid on a substantially waterproof base, of means for introducing liquid to said beach at a point below 45 the surface of the sand, and means for withdrawing said liquid from said beach from a point below the surface of the sand.

2. The combination with a sand beach laid on a substantially waterproof base, of means for 50 cleaning and smoothing the beach comprising, a liquid inlet communicating with the body of sand at a point below the surface thereof, a curb upstanding above the surface of the sand and provided with an overflow gutter, means for supplying liquid through said inlet to overflow said curb, and a liquid outlet communicating with the body of sand below the surface thereof.

3. In combination, a pool, a trough surrounding 55 said pool and substantially filled with sand, a conduit providing communication between said pool and said trough and opening into said trough at a point below the level of sand therein, and a conduit communicating with said trough at a point below the level of sand therein for withdrawing liquid from said trough.

4. In combination, a pool, a trough surrounding 60 said pool and substantially filled with sand, the level of sand in said trough being below the normal water level in said pool, a conduit providing communication between said pool and said trough and opening into said trough at a point below the level of sand therein, and a conduit 65 communicating with said trough at a point below the level of sand therein for withdrawing liquid from said trough.

5. In combination, a pool, a trough surrounding 70 said pool and substantially filled with sand, the outer perimetral wall of said trough extending above the level of sand in said trough, but terminating below the normal water level in said pool, a conduit providing communication between said pool and said trough and opening into said trough at a point below the level of sand therein, and a conduit 75 communicating with said trough at a point below the level of sand therein for withdrawing liquid from said trough.

6. A device of the class described comprising a basin having a bottom and upstanding side walls, a sump beneath said basin, said basin bottom being apertured to afford direct communication 15 between said basin and a part of said sump, a baffle depending from said basin bottom and projecting downwardly into said sump but terminating short of the bottom of said sump, comminuted material filling said basin to a level below the upper ends of said side walls and partially filling said sump, such material defining, with 20 said basin wall and said baffle, a chamber within said sump unfilled by such material, a liquid inlet opening into said sump, and a liquid outlet 25 opening from said chamber.

7. A device of the class described comprising a basin having a bottom and upstanding side walls, the upper end of one of said walls being lower than the upper end of another of said walls, a 30 sump beneath said basin, said basin bottom being apertured to afford direct communication between said basin and a part of said sump, a baffle depending from said basin bottom and projecting downwardly into said sump but terminating short 35 of the bottom of said sump, comminuted material filling said basin to a level below the upper ends of said side walls and partially filling said sump, such material defining, with said basin wall and said baffle, a chamber within said sump unfilled 40 by such material, a liquid inlet opening into said sump, a source of liquid supply connected to said inlet and adapted to supply liquid to said basin to overflow said one wall, and a liquid outlet opening from said chamber.

8. The method of sterilizing a mass of comminuted material which comprises the steps of passing a sterilizing fluid upwardly through such mass, and then passing such fluid downwardly 50 through such mass and withdrawing the fluid.

9. The method of sterilizing a mass of comminuted material which comprises the steps of passing a sterilizing fluid upwardly through such mass to build up a body of fluid upon the surface of such mass and permeating such mass, permitting such fluid body to stand for a period, and then withdrawing such fluid body downwardly 55 through such mass.

10. The method of cleaning, smoothing, and sterilizing a mass of comminuted material which 60 comprises the steps of supplying a sterilizing liquid to such mass at a point below the level of such mass, building up a body of liquid, from such supply, to a level above the surface of said mass, and thereafter withdrawing such liquid at 65 a point below the surface of said mass.

11. The method of cleaning, smoothing, and sterilizing a mass of comminuted material which 70 comprises the steps of supplying a sterilizing liquid to such mass at a point below the level of such mass, building up a body of liquid, from such supply, to a level above the surface of said mass, whereby flotsam is lifted from the surface of said mass, permitting a surface overflow of such liquid to carry away such flotsam, while 75

maintaining such supply, and thereafter withdrawing such liquid at a point below the surface of said mass.

12. The method of cleaning, smoothing, and sterilizing a sand beach adjacent a pool of chlorinated water which comprises the steps of maintaining a liquid level in said pool above the sand level of said beach, establishing communication between said pool and a point within the mass 5 of sand below the surface of such sand, whereby a body of chlorinated water is built up on said beach substantially to the level of liquid in said pool, cutting off such communication, and thereafter withdrawing such water from said beach 10 at a point below the surface of the sand mass.

13. The method of cleaning, smoothing, and

sterilizing a sand beach adjacent a pool of chlorinated water which comprises the steps of maintaining a liquid level in said pool above the sand level of said beach and above the level of a bounding wall of said beach, establishing communication between said pool and a point within the mass of sand below the surface of such sand, whereby a body of chlorinated water is built up on said beach substantially to the level of liquid in said pool and whereby flotsam lifted from said mass is entrained and carried away with the surface overflow over said bounding wall, cutting off such communication, and thereafter withdrawing such water from said beach at a point 15 below the surface of the sand mass.
